UNITED STATES PATENT OFFICE.

OTTO RECHNITZ, OF COTTBUS, GERMANY.

FOUNDATION ON WHICH PLASTER MAY BE LAID.

1,107,841.

Specification of Letters Patent.

Patented Aug. 18, 1914.

Application filed February 20, 1911. Serial No. 609,621.

To all whom it may concern:

Be it known that I, OTTO RECHNITZ, merchant, a subject of the German Emperor, residing at 1 Kaiserstrasse, Cottbus, Germany, 5 have invented certain new and useful Improvements in Foundations on Which Plaster May be Laid, of which the following is a specification.

My invention relates to lathing on which 10 plaster may be laid, and a primary object is to provide an improved process of manufacturing foldable lathing of the character referred to comprising ready-made bodies of clay or other suitable building material 15 secured in the meshes of woven wire or wire netting.

The following are some advantages of my process: Firstly, the wire fabric or netting does not have to be exposed, as heretofore, 20 together with the unburnt bodies to the heat of the fire, secondly, water is not requisite, as in fabrics covered with mortar, for making the lathing and, thirdly, on the one hand the wire netting and, on the other 25 hand, the bodies which can be made in works for making artificial stone or in brick-works, can be made separately in the suitable works and therefore both better and cheaper.

My process may be carried into practice in 30 various ways. For example, the bodies of clay, mortar or other suitable material, hereinafter referred to generally as bodies, may be secured in position at the same time as the wire netting is being made by their being 35 woven into the wire netting. This can be done by inserting a body into an open mesh shortly before the latter is closed and by securing the body in position by closing the mesh. The wire netting may, however, be 40 made quite independently of the insertion of the bodies. In this event the individual bodies may be inserted into the meshes and secured therein by exerting a pull on said netting and bringing the same under tension 45 so as to elongate the meshes thereof in one direction and contract said meshes in a direction transverse to said first named direction and consequently cause the netting to grip and hold said bodies securely in place. 50 This latter operation instead of being performed after the netting has been completed can, however, take place during the manufacture thereof in such manner that after

making one or more meshes and after inserting bodies into the same, the latter are 55 secured in position by changing the shape of the meshes. This change in the shape of the meshes is preferably brought about by taking advantage of the tension exerted in the direction in which said meshes are being 60 made. Lastly, the wire netting may be completely finished and the individual bodies then be pushed by force into its meshes, for example, in such manner that, when forcing 65 them in, the wires of the meshes yield and by springing back into suitable recesses provided in the bodies, securely hold the latter.

In the accompanying drawings Figure 1 represents an edge view of one of the bodies referred to hereinbefore and Fig. 2 is a face 70 view of a section of the completed lathing.

In said drawings *a* designates bodies made for instance of clay, mortar or other suitable material and *b* represents the wire netting with which said bodies are combined to form 75 the completed lathing.

I claim:-

1. The herein described process of producing flexible lathing for plaster which consists in taking bodies of clay, cement or the like, shaping same and forming a circumferential recess therein, bringing said bodies to a finished, rigid condition, constructing a wire netting with meshes adapted to readily receive said bodies, inserting said finished 80 and rigid bodies into some of the meshes of said netting, and changing the shape of said meshes by exerting a tension on said netting and thereby causing the meshes thereof to become contracted in one direction and the 85 netting to enter said grooves and grip said bodies.

2. The herein described process of producing flexible lathing for plaster which consists in taking bodies of clay, cement or the like, shaping same and forming a circumferential groove therein, bringing said bodies to a completely finished condition, constructing a wire netting, inserting said completely finished bodies into the meshes thereof and 95 subsequently changing the shape of said meshes so that the wires forming the netting will enter the grooves of said bodies and grip the latter.

3. The herein described process of producing flexible lathing for plaster which con-

sists in taking bodies of clay, cement or the like, shaping same and forming a circumferential groove therein, bringing said bodies to a completely finished condition, constructing a wire netting having meshes adapted to be closed, inserting therein the said completely finished bodies before said meshes are closed and thereafter closing said meshes whereby the wires forming the netting will

enter the grooves of said bodies and grip 10 the latter.

In testimony whereof I hereunto affix my signature in presence of two witnesses.

OTTO RECHNITZ.
